[57] CLAIM

The ornamental design for an air freshener dispenser, as shown and described.

DESCRIPTION

FIG. 1 is a top, right side and front perspective view of an air freshener dispenser showing our new design;
FIG. 2 is a front elevation view thereof;
FIG. 3 is a right side elevation view thereof;
FIG. 4 is a left side elevation view thereof;
FIG. 5 is a top plan view thereof;
FIG. 6 is a bottom plan view thereof;
FIG. 7 is a rear elevation view thereof; and,
FIG. 8 is a left side elevation view of an air freshener dispenser showing a second embodiment of our new design, the sole difference residing in the bottom container being opaque.
